METHOD OF IMPROVING PRODUCTION OF PETROLEUM FROM AN UNDERGROUND RESERVOIR

Donald L. Hoyt, Houston, Tex., assignor to Texaco Inc., New York, N.Y., a corporation of Delaware
Filed Apr. 11, 1960, Ser. No. 21,485
5 Claims. (Cl. 166—9)

This invention relates generally to the recovery of petroleum from underground reservoirs. More particularly, this invention relates to a method for improving the recovery of petroleum from an underground petroleum-producing reservoir. In a specific embodiment, this invention is directed to the production of petroleum from an underground petroleum-producing formation which is under the influence of an adjacent, e.g. underlying, water-producing formation or aquifer.

In the production of petroleum from underground formations, it has been the practice heretofore to penetrate the petroleum-producing formation with a plurality of wells arranged in a grid pattern, the petroleum being produced from the formation via these wells. It has been observed particularly when the petroleum-producing formation is a so-called water drive formation, i.e. under the influence of a water-producing formation which tends to displace the petroleum from the petroleum-producing formation via the production wells, that the wells around the periphery of the producing formation relatively quickly produce an excessive amount of water and must be abandoned before substantially all of the petroleum in that zone of the formation under the influence of these peripheral wells has been produced.

Accordingly, it is an object of this invention to provide a method for improving the production or recovery of petroleum from an underground petroleum-producing formation.

Another object of this invention is to provide an improved method for the production and recovery of petroleum from an elongated, substantially elliptical, petroleum-producing formation which is under the influence of an adjacent water-producing formation.

Another object of this invention is to provide a method for increasing the amount of oil which is recovered from an underground, water drive, petroleum-producing formation.

Still another object of this invention is to provide an improved method for producing a water drive petroleum-producing formation during primary depletion as well as during secondary recovery operations.

How these and other objects of this invention are accomplished will become apparent from the following description when read in conjunction with the accompanying drawings wherein FIGS. 1, 2, 3 and 4 schematically illustrate the distribution of petroleum-producing wells producing an elongated petroleum-producing formation.

FIGS. 5 and 6 are graphical showings of results achieved respectively by conventional practice and by practice of this invention.

In accordance with this invention, it has been discovered that the production of petroleum from an underground petroleum-producing formation is improved by disposing the production wells producing the formation substantially in line along the length of the producing formation.

2

More particularly, it has been discovered that the petroleum production from an underground, elongated, substantially elliptical, petroleum-producing formation, which is under the influence of a water drive, is improved by disposing the production wells penetrating the formation substantially in line along the major axis of the formation.

Still more particularly, in accordance with this invention, it has been discovered that the production of petroleum from an underground, elongated, substantially elliptical, water drive petroleum-producing formation is improved by disposing the production wells producing the formation so that as many of the production wells as practicable are disposed substantially in line along (i.e. on or near) the major axis of the formation.

As indicated hereinbefore, the practice of this invention is applicable particularly to improving the recovery of petroleum from elongated, substantially elliptical, water drive petroleum-producing formations. More particularly, improved results are obtained in accordance with the practice of this invention when the elongated, substantially elliptical, petroleum-producing formation has a major axis at least four times greater than the minor axis, e.g. a ratio of major axis to minor axis in the range of about 4.5—10.0 to 1.0.

Referring now to the accompanying drawings, particularly to FIG. 1 thereof, there is illustrated schematically therein an elongated, substantially elliptical water drive petroleum-producing formation wherein the major axis thereof has a length about 4.5 times greater than the minor axis. The periphery of this reservoir is delineated by ellipse 10. Penetrating the elliptical reservoir 10 is a plurality of production wells P, for a total of 34 production wells. Of these production wells, 12 or 35 percent of the total number are disposed in line along the major axis of the formation and equidistant from each other. The remaining production wells, P, 22 in number, are disposed, as indicated, in a grid-like pattern with respect to the aforementioned production wells disposed in line along the major axis of the formation. Laboratory tests on a model simulating the above-described elliptical reservoir indicated that when all the wells are produced simultaneously, there is ultimately swept about 86.4 percent of the oil in place in the reservoir, i.e. during production of this reservoir via the 34 production wells, 86.4 percent of the reservoir formation was swept by the displacing fluid (water).

On the other hand, tests conducted on the same reservoir having a total of 46 production wells, 12 or 26 percent of which are disposed in line along the major axis thereof, as illustrated in accompanying FIG. 2, indicated that only 86.4 percent of the reservoir was swept. Upon comparison of the results obtained with the petroleum production techniques as disclosed in FIGS. 1 and 2, it is seen that the 12 additional wells employed in connection with FIG. 2 did not contribute to any additional production of petroleum from the reservoir and represented, in fact, a substantially needless expenditure.

FIG. 3 represents the same reservoir again having a total of 46 production wells, but this time 16 or about 35 percent of which are disposed substantially in line along the major axis thereof. Tests carried out in connection with the production wells disposed in the manner illustrated in FIG. 3 indicated that 90.7 percent of the petroleum-producing formation would have been swept, with resulting increase in the production of petroleum. Further, since the total number of wells has been in-

creased, it is possible to deplete the reservoir in a much shorter period of time along with the substantial increase in petroleum production.

Finally, the same water drive petroleum-producing formation was again simulated and this time all the production wells, a total of 12 in number, were disposed in line along the major axis of the formation. The laboratory tests carried out in connection with the well arrangement set forth in FIG. 4, wherein all the production wells are disposed in line along the major axis of the formation, showed that such an elongated, elliptical water drive formation would be produced to the extent of 88.1 percent thereof by these 12 wells alone, i.e. 88.1 percent of the formation would be swept. Although the rate at which petroleum is produced from such a formation is less than the rate of production from the same formation by employing a larger number of production wells in the manner indicated in FIGS. 1 through 3, still the overall recovery is high, and higher than that exhibited by the tests carried out with respect to the well arrangements illustrated in FIGS. 1 and 2, so that substantially less capital expenditure is required to exploit a petroleum-producing formation in accordance with the well arrangement of FIG. 4.

The problem of optimum well density, or spacing, to deplete a producing field has many facets. It is only natural that a producer would wish to get the greatest possible volume of oil from his various reservoirs and also to do it with the least possible number of wells. Assuming that recovery is proportional to the area swept out, any curve of recovery versus the number of wells is influenced by such factors as:

- (1) The shape of the field.
- (2) Source and type of drive.
- (3) Types of production and injection well patterns.
- (4) Permeability distributions.
- (5) Gravitational forces.
- (6) Field production practices.

In an investigation concerning these tabulated factors, it is obvious that an increase in sweepout will not be a linear function of the number of wells. Somewhere on the slope of any curve showing the plot of these variables, there will begin a decrease and probably very sharply. To include an evaluation of the relative effects of all of the factors mentioned above would require a tremendous amount of time and effort, so that certain logical starting points and assumptions for a study are required. As an example, the shape of a field may be assumed as an ideal model, to be uniformly thick, nearly flat and elliptical, such type of field occurring in the petroleum producing formations adjacent the Persian Gulf. Further, permeability variations need not be considered since their effect would be present for each value of the total number of wells investigated and would tend to cancel each other.

A study of the sweep-out (R) versus the number of wells (N) in the field yielded the data listed in Table I, below, showing the measured values of R versus N, together with the number of wells on the axis (n).

Table I

Number of wells N	Percent swept R	Wells on axis n	Number of wells N	Percent swept R	Wells on axis n
11	26.6	1	17	72.0	5
12	30.9	2	19	76.6	7
13	51.5	3	23	77.3	7
4	12.0	0	25	79.6	9
5	32.6	1	28	83.3	10
6	59.7	4	31	84.2	11
7	53.1	3	34	86.4	12
8	48.8	2	40	88.3	14
9	67.4	5	46	86.4	12
10	62.4	4	46	90.7	16
11	88.1	12	69	95.4	25
13	71.2	5			

¹ No pattern; wells only on axis.

FIG. 5 is a chart of part of this data, where it can be seen that there is no definite break in the curve. There is also some scatter, particularly in the lower values of N, where an increase in N sometimes results in a decrease in R.

FIG. 6 is a plot of R versus n which produces a much smoother curve than that disclosed in FIG. 5 and has no instance of a decrease in R for an increase in n. There appears to be a break in the curve where the value of n is equal to 6 or 7 and a levelling off at about n equals 25 (and R equals 95 percent). Beyond this value, the curve will still approach 100 percent as n approaches infinity but the slope is very small. Measurement of the slope of the curve for values of n greater than 25 shows that the slope can be less than $\frac{1}{2}$ percent per well, so that additional data points would not be reliable enough to warrant the time required for further study.

The data in Table I for R, N and n indicates quite clearly that the sweep-out is not nearly so dependent on N as on n. Tests which utilize the same number of axial wells tend to have the same or nearly the same sweep, even though the total number of wells may differ considerably. This is true especially for the higher values of n. The plot in FIG. 6 when weighed in conjunction with other factors, helps to determine the best number of axial wells to use. Sweep-out of approximately 95 percent of the areal extent of the reservoir may be achieved with as few as 25-30 wells.

It is recognized that when a field is discovered, a certain number of development wells will always be required in order to delineate field boundaries and obtain necessary information. It is recognized further that the maximum well potential and the total field production requirement will establish a minimum number of wells to be in operation. In other words, the principles described above, when applied to a producing field will tend to yield the optimum sweep-out of a typical elongated field.

Although in the practice of this invention, particular emphasis has been placed on the exploitation of elongated, substantially elliptical, water drive reservoir, the production techniques of this invention are also applicable to so-called gas-drive reservoirs and indeed are generally applicable to large, elongated reservoirs wherein the ratio (l/w) of the length (l) to the width (w) thereof is greater than 4. The elongated reservoir applicable in the practice of this invention need not be substantially elliptical in shape but may be curved, angled or serpentine in configuration, provided the ratio of the overall length to the overall or average width of the formation (l/w) is at least greater than 4.

As will be apparent to those skilled in the art, in the light of the accompanying disclosure, many changes, alterations and substitutions are possible in the practice of this invention without departing from the spirit and scope thereof.

I claim:

1. A method of producing petroleum from a uniformly thick, nearly flat, underground petroleum-bearing formation, elongated and substantially elliptical in shape with the ratio (a/b) of the major axis (a) of said formation to the minor axis (b) thereof being greater than four, which comprises penetrating said formation with a plurality of production wells, and producing petroleum from said formation via said production wells, the number of said production wells disposed substantially in line along said major axis of said formation varying from 5 to 30.
2. A method in accordance with claim 1, wherein the production wells disposed substantially in line along said major axis are substantially equidistant from each other.
3. A method in accordance with claim 1, wherein all the production wells penetrating said formation are disposed substantially in line along the major axis.

4. A method in accordance with claim 1 wherein the number of production wells disposed substantially in line along the major axis of said formation is at least the majority thereof.

5. A method in accordance with claim 1 wherein said formation is under the influence of and in contact with a water-producing formation.
